Geo. P. Kimmel, ATTORNEY.

UNITED STATES PATENT OFFICE.

RALPH S. THOMPSON, OF NEW YORK, AND CARL F. DOSCHER, OF WHITE PLAINS, NEW YORK, ASSIGNORS TO THE THOMPSON-BARLOW COMPANY, INC.

MASSAGE APPARATUS.

Application filed July 12, 1921. Serial No. 484,056.

To all whom it may concern:

Be it known that we, RALPH S. THOMPSON and CARL F. DOSCHER, citizens of the United States, residing at New York, in the county 5 of New York and State of New York, and White Plains, in the county of Westchester and State of New York, respectively, have invented certain new and useful Improvements in Massage Apparatus, of which the 10 following is a specification.

This invention relates to massage apparatus operating on the suction principle and is especially adapted for use in massaging various parts of the human body.

15 The primary object of the invention is to provide a device of this character equipped with pressure regulating means whereby the device may be used as gently or as briskly as desired, and which is constructed to break 20 up congested fatty condition and bring the normal flow of blood to the spot massaged thereby causing it to course through the tissues.

Another object is to provide a combined 25 flesh manipulator and blood circulator with means for loosening fatty congestion to effect its quick and easy dissolution.

Another object is to provide a device of 30 this character controllable by the manipulator to hold the flesh as firmly or as gently as may be desired and by a slight rotating motion to give concentrated exercise.

Still another object is to provide a vacuum cup equipped with means for regulating 35 the strength of the vacuum at will.

Another object is to so construct a vacuum cup that the operator may release the vacuum without having to forcibly remove the cup.

40 With these and other objects in view the invention consists in certain novel features of construction as hereinafter shown and described and then specifically pointed out in the claims and the drawings illustrative 45 of the preferred embodiment of the invention.

In the accompanying drawings:—

Figure 1 is a plan view of a massage apparatus or device in accordance with this 50 invention, and

Figure 2 is a central vertical view thereof.

In the embodiment of the invention, as illustrated, it includes what may be termed a body portion generally referred to by the reference character 1, and in the form of a 55 vacuum cup constructed of soft rubber. The body portion 1, consists of an outer portion 2, an inner portion 3 and an intermediate portion 4. The intermediate portion 4 is of less thickness than the outer 60 portion 2, or the inner portion 3. The outer portion 2 is of greater thickness than the inner portion 3. The outer portion 2 gradually increases in thickness from the intermediate portion 4, to the free terminus of 65 said outer portion 2. The inner portion 3 gradually increases in thickness from the intermediate portion 4 to the outer terminus of said inner portion 3. The free terminus of the outer portion 2, is formed with a 70 laterally extending annular flange 8, thereby providing an extended seating edge or flat surface engaging surface 7. The flange 8 is flush with the free terminus of the outer portion 2. 75

The inner portion 3 terminates in an elongated shank or stem 9, formed with an annular rib 10 for reinforcing purposes, and said stem 9, is furthermore provided with a laterally projecting annular head 11, 80 spaced from the rib 10, and the latter and the head 11 are of such contour as to provide the stem 9 with a peripheral annular groove 12, semi-cylindrical in section and which constitutes means whereby the shank 85 can be conveniently gripped and held in position.

Extended from the head 11 is a tapering protuberance 6, which is formed with a flaring opening 13, the latter opens into a flared 90 port 14 of less diameter throughout than the opening 13. The flared port 14, is formed centrally of the head 11. The stem 9, is formed with a flaring channel 5, of greater diameter throughout than the port 14, and the latter at its smaller end communicates with the smaller end of the channel 5. The flare of the channel 5 extends in an opposite direction with respect to the flare of the port 14, and also with respect to the flare of 100

the opening 13. The channel 5, port 14 and opening 13 provide the shank or stem with a centrally disposed bore, restricted in diameter intermediate its ends through 5 the medium of the size of the port 14 and the manner of setting up said port 14 with respect to the opening 13 and channel 5. The shank 9 and protuberance 6 form what may be termed a handle element and which 10 is integral with the body portion 1, and also constructed of soft rubber providing for the expansion and contraction of said element when occasion requires.

The opening 13 forms what may be 15 termed the mouth of the bore of the handle element.

The handle element is employed for operating the device and the bore therein enables the operator to regulate the strength of the 20 vacuum.

As the intermediate portion 4 of the body portion 1, is of less thickness than the inner portion 3 or the outer portion 2, when the body portion 1 is compressed by the operator, the intermediate portion 4 will be forced inwardly with respect to the outer portion 2, as the outer terminus of the intermediate portion 4 will be caused to swing inwardly on the inner terminus of the outer 25 portion 2, as the said intermediate portion 4 is shifted inwardly with respect to the outer portion 2, through the medium of the inner portion 3, providing what may be termed a shoulder which will be brought 30 into contact with that part of the human body inclosed within the outer portion 2.

In the use of this massage apparatus or device, the body portion 1, which is intended primarily as a flesh reducer, is placed upon 40 the fleshy part to be massaged and the handle member or element then pressed down which will produce a vacuum and cause the outer portion 2 and intermediate portion 4 to take hold of the part to be massaged. 45 Before releasing the body portion 1, the finger of the operator is placed over the opening 13, and a small rotary movement is imparted to the body portion 1, or rather to the handle element. The body portion 1, 50 grasps the flesh owing to the vacuum produced therein and the rotary movement imparted thereto is transmitted to the flesh grasped thereby, and breaks up the congested fatty condition of parts massaged 55 and causes the normal flow of blood to be brought to the spot manipulated and the blood to flow through the fleshy tissues and quickly carry off the fatty congestion.

It is well known that fat accumulates in 60 the human body because the blood circulation is not sufficiently active to carry it off and that the formation of excess fat finally renders it impossible for the blood to course through it.

Science has proven that the creation of

abundant circulation in the part affected with surplus fat will operate to carry away the surplus fatty tissue, and it is along this line that this invention is designed to operate and in addition to producing abundant circulation the device constituting this invention operates to successfully soften and loosen the fleshy formation and to harmlessly disintegrate it whereby the blood will be enabled to circulate freely and to quickly 75 carry off the fatty congestion.

It will thus be seen that the cup which constitutes this invention and which may be termed a reducing cup operates first to manipulate the flesh and increase the blood 80 circulation around the fatty portion and secondly to loosen the fatty congestion to enable it to be quickly and easily dissolved. The cup operates on the suction principle 85 and holds the flesh as firmly or as gently as desired and by a slight rotary motion produces concentrated exercise in a manner which will quickly dissolve superfluous fat.

The body portion 1, has its outer face formed of what may be termed of O-gee 90 curvature and the inner face of the body portion 1, at the outer portion 2 flares outwardly and then extends inwardly on what may be termed a compound curve. The inner portion 3 is of less diameter than the intermediate portion 4, and the outer portion 2 is of greater diameter than the intermediate portion 4.

The head 11 which may be termed a pressure regulator enables the cup to be used 100 either gently or briskly and the straight flat edge of the mouth of said cup provides for the firm gripping of the flesh by the cup.

From the above description it will be obvious that this cup may be used to massage any part of the human body wherever there is an undesired or excessive accumulation of surplus fat and that the use thereof will actually remove the superfluous fat at 105 any point desired without employing any unnecessary or harmful methods.

It is of course understood that the operator is to place his finger over the opening 13 leading from the port 14 for controlling 110 the vacuum pressure and when desired to release the pressure he simply removes his finger.

Moreover the flange 8 in connection with the edge 7 of the cup mouth provides a 115 flexible contact lip adapted to exclude air to insure a vacuum in the cup when said cup is applied.

The preferred embodiment of the invention is disclosed in the drawings and set forth in the specification, but it will be understood that any modifications within the scope of the claimed invention may be made in the construction without departing from the principle of the invention or sacrificing 125 any of its advantages.

What we claim is:—

into said inner portion of said body and said flaring opening sealed by one of the fingers employed for depressing said outer portion, the inner diameter of said inner portion gradually increasing toward said outer portion and the inner face of said inner portion being continuous throughout,

and said outer portion being of compound curvature and decreasing in diameter from said inner portion.

10

In testimony whereof, we affix our signatures hereto,

RALPH S. THOMPSON.
CARL F. DOSCHER.
